UNITED STATES PATENT OFFICE.

MILTON SABIN, OF NEW YORK, N. Y., ASSIGNOR TO ALEX. SABIN & SONS, OF NEW YORK, N. Y.

CHAIN.

Application filed July 31, 1926. Serial No. 126,215.

This invention relates to mesh fabric used for bracelets, watch fobs and the like.

The principal object of the invention is the provision of means to prevent unraveling of the mesh fabric.

Another object of the invention is to solder a pair of cables at the sides of the mesh fabric in order to prevent the unraveling of said fabric.

Still another object of the invention is the provision of means to prevent stretching of the mesh fabric without losing any of its flexibility.

Other objects of the invention will appear as the disclosure progresses. The drawings are intended merely to indicate a possible embodiment of the invention. It is obvious that the actual needs of manufacture may necessitate certain mechanical changes. It is therefore not intended to limit the invention to the embodiment illustrated, but rather to define such limits in the appended claim.

For a more detailed understanding of the invention, attention is now called to the drawings in which a preferred embodiment is shown illustrated. In these drawings, like parts are designated by like reference characters in all the views.

Fig. 1 is a view of the mesh fabric with the cables attached thereto.

Fig. 2 is an enlarged fragmentary portion thereof.

Fig. 3 is a similar view as Fig. 2 with different type of cables.

Fig. 4 is a section on line 4-4 of Fig. 2.

Fig. 5 is a section on line 5-5 of Fig. 3.

Fig. 6 is a modified form of the cable.

Fig. 7 is an end view thereof.

Referring now more particularly to the drawings, numeral 1 designates the mesh

fabric and 2 the cables attached to both sides of the mesh fabric preferably by solder S for the purpose of preventing the fabric from unraveling.

As noted in Fig. 4 the cables 2 are attached to the chain by positioning the links 3 and 4 diagonally to each other so that the upper end of link 4 and lower end of link 3 connect to the mesh fabric. This construction makes a very secure bond between the cables and chain and allows the chain to bend very freely.

The cables will not only prevent the chain from unraveling but also its stretching.

In Fig. 3 is shown a modified form of the cable in which the box links 5 are formed of solid sections so precious stones 6 can be set therein or in lieu thereof the box links can be engraved and thereby make a pleasing appearance. The links 5 are formed with a male and female member 7 and 8 and are hinged together by pins 9.

Figs. 6 and 7 show a modified form of the cables in which numeral 10 designates the boxes for the settings and 11 the links for joining them together.

It will thus be seen that I have provided an efficient means to prevent the unraveling of the mesh fabric.

I claim:

In a device of the class described in combination, a mesh fabric having a continuous flexible chain attached to both edges thereof to prevent the said fabric from unraveling, the entire length of each link of said chain rigidly secured to the edge of said fabric throughout the entire length of the fabric.

In testimony whereof I affix my signature.

MILTON SABIN.
